FILLING MACHINE

Edward G. Bauer, Hoopeston, Ill., assignor to Food Machinery Corporation, San Jose, Calif., a corporation of Delaware

Application July 25, 1940, Serial No. 347,362

12 Claims. (CL 226—96)

This invention relates to machines for filling containers, such as cans and jars, with food commodities, particularly cut vegetables, such as: sliced beets, cut string beans, diced beets, diced carrots, diced potatoes, mixed diced vegetables, shoe string beans, shoe string carrots, and shoe string potatoes.

A machine of the type with which the invention is concerned is disclosed in the patent to W. F. Christel, No. 2,150,490, issued March 14, 1939. In machines of this type the cans are carried around in a circle with their openings in registry with filling openings in the periphery of a revolving table. The material is filled into the cans through a hopper positioned above the filling openings in the table and in the path of travel thereof.

One object of the invention is to provide an improved feeding means in the hopper of a filling machine of this type to facilitate transfer of the material from the hopper to the filling openings in the revolving table.

Another object is to provide an improved screw construction in the outlet of the hopper which will speed up the discharge of material from the hopper by preventing material, like cut string beans, from clogging the outlet.

A further object is to provide an improved wiper for removing excess material from the container after it has been filled from the hopper.

Other objects will become apparent after the disclosure of a machine in which the invention has been embodied.

In the drawings:

Fig. 1 is a plan view of the filling machine showing the hopper mounted thereon at the left side of the view.

Fig. 2 is a section through the wiper taken as indicated by the line 2—2 in Fig. 1.

Fig. 3 is a fragmentary section through the hopper and table taken vertically along the longitudinal axis of the feed screw, as indicated by the arrows 3—3 in Fig. 1.

Fig. 4 is a vertical sectional view of the upper portion of the machine. The section is taken as indicated by the arrows 4—4 in Fig. 1.

Fig. 5 is a side elevation of the wiper taken as indicated by the arrows 5—5 in Fig. 2.

The machine comprises a revolving table 10 (Figs. 1 and 4) having a series of filling openings 11 arranged around its periphery. Each filling opening 11 has a downwardly projecting lip 12 for fitting into the open end of the can. The central portion 13 of the table 10 is depressed to form a bowl for the reception of excess material.

The table 10 is supported upon and rigidly secured to the wheel 14 having a central protuberance 15 for supporting the center of the bowl portion 13 and having an upstanding peripheral flange 16 for supporting the peripheral portion of the table 10. A feed ring 17 is secured to the wheel 14 and is provided with feed fingers 18. Intermediate the fingers 18 are formed arcuate openings or pockets 19 into which the cans fit and which serve to center the cans in registry with the filling openings 11.

A stationary track 20 comprising two spaced-apart concentric rails 21, 22 is provided for supporting the cans during their travel around with the table, the fingers 18 engaging the walls of the cans to advance the cans along the track 20. As shown in Fig. 4, the rails 21 and 22 are mounted in fixed position by means of brackets 23 attached to the frame 24 of the machine. A circular fixed guide rail 25 is supported on brackets 26 concentric with the table 10 to retain the cans in the arcuate openings 19 of the feed ring 17.

The wheel 14 to which the table 10 and feed ring 17 are secured is supported on a vertical shaft 27 (Fig. 4), the upper end of which is received in the bore of the hub 28 of the wheel 14. The lower end of the hub 28 bears against a collar 29 secured to the shaft 27 by a pin 30. The shaft 27 is supported by a worm wheel 31, into the hub 32 of which the shaft 27 is threaded. The worm wheel 31 is supported in a bearing 33 mounted in the central portion 34 of the machine framework 24.

In order to transmit rotation from the worm wheel 31 to the wheel 14 the latter is provided with plunger rods 35 secured in bosses 36 formed integrally with the table 10. The rods 35 slidably engage bores 37 formed in upstanding bosses 38 on the worm wheel 31. A set screw 39 is threaded through the hub 32 of the worm wheel and bears against the shaft 27 to lock the worm wheel and shaft together in any adjusted position. The threaded shaft 27 is rotated to raise and lower the table 10 with respect to the track 20 in order to enable the machine to accommodate cans of different height. Rotation of the worm wheel 31 is transmitted through the rods 35 to the wheel 14 so that the table 10 rotates in unison with the worm wheel 31.

The means for driving the worm wheel 31 is shown in phantom in Fig. 1. The worm wheel 31 is driven by a worm 40 on a shaft 41 which is driven from a power shaft 42 by bevel gears 43. The outer end of the power shaft 42 has a pulley

44 adapted to be driven from a source of power not shown.

Suitable means of well-known construction are provided for feeding the cans into the machine and for discharging them therefrom. The feeding means comprises a rotary disc 50 on which the empty cans are deposited. A stationary guide 51 is positioned above the disc to direct the cans toward the feed ring 17. A spring-pressed pivoted arm device 52 admits the cans one by one to the pockets 19 and the fingers 18 transfer the cans from the disc to the track 20. The beginning of the guide rail 25 projects over the disc to guide the cans into the pockets 19 and retain them therein. The cans are thus carried around in registry with the filling openings 11.

After the cans are filled, by mechanism presently to be described, they are deposited on a rotary discharge disc 53. The ends 54 and 55 of the track and guide rail project out over the disc 53. The fingers 18 move the cans off the end of the track onto the disc. A stationary rake 56 projects under the feed ring 17 to intercept the cans and remove them from the pockets 19. An arcuate portion 57 of the rake directs the filled cans around in the direction of rotation of the discharge disc 53.

A supply of the material to be filled in the cans is contained in a feed hopper 60 (Fig. 1) which comprises a sheet-metal funnel-shaped portion 61 (Figs. 3 and 4) mounted on a base casting 62. The inner wall 63 (Fig. 4) and the end wall 64 (Fig. 3) of the hopper are substantially vertical. The outer wall 65 (Fig. 4) and the end wall 66 (Fig. 3) are inclined. The discharge outlet of the hopper is an opening 67 formed in the base 62. The opening 67 (Figs. 1 and 3) is elongated and the hopper is mounted on the machine in a position where the filling openings 11 will move under the opening as the table 10 revolves in the direction of the arrow placed thereon in Fig. 1, and will remain in registry with the opening during the whole time they are under the hopper by reason of the elongated conformation of the opening 67. The hopper 60 (Fig. 4) is supported in the required position above the revolving table 10 by means of two posts 68, one of which appears in Fig. 4, which are secured at their upper ends in the hopper base 62 and which project down through holes in a bracket 69 secured to the machine frame 24. The hopper is lowered until the base 62 just clears the table 10, then the set screws 69' are tightened to hold the posts 68 in place.

A feeding means 70 is disposed in the bottom of the hopper 60 above the hopper outlet 67 to aid the discharge of material down through the filling openings 11 into the cans positioned therebeneath. The feeding means 70 comprises a shaft 71 journaled in bearings 72, 73 (Fig. 3) in the base casting 62. The shaft 71 has a screw thread 74 thereon, the outside diameter of which gradually diminishes from right to left in Fig. 3, or in the opposite direction to the direction of movement of the cans which is indicated by the arrow 75. One end of the shaft 71 is connected to the shaft 41 (Fig. 1) by a flexible drive 76 which rotates the shaft 71 to cause the screw thread 74 to feed the material to the left in Fig. 3 in the direction of the arrow 75.

The screw thread 74 at the maximum diameter end merges into a disc 78 (Fig. 3). At the minimum diameter end it merges into the body of the shaft 71 and terminates at 79. The terminus 79 of the thread is located at a distance, amounting

to substantially the diameter of the filling opening 11, from the left end of the hopper in Fig. 3, and at the margin of a zone 80 in the hopper where the material descends vertically into the can. This zone 80 is bounded by the left end wall 66 of the hopper and the imaginary margin of the other side of the zone is indicated by the dot-and-dash line 81. Situated intermediate the end wall of the hopper and the terminus 79 of the screw thread in the zone 80 is a rotary feeder 82, comprising a pin secured transversely in the shaft 71 with its ends 83, 84 extending radially therefrom.

The operation of the feeding means 70 in the bottom of the hopper 60 is as follows: The cans 85, 86, 87 (Fig. 3) are being slid along the stationary track 20 in the direction of the arrow 75 by the fingers 18 of the feed ring 17. The table 10 is moving in unison with the feed ring 17 so that the filling openings 11 are over the cans.

The filling opening 11 over the can 85 has just come into communication with the discharge outlet 67 of the hopper. The material in the vertical feed zone 80 above the can 85 immediately moves downwardly. The can is rapidly filled at this point by reason of the fact that the material in the zone 80 has a direct vertical passage, unobstructed except for the shaft 71, as best illustrated in Fig. 1. The material descends rapidly in this zone not only because of the direct gravity path available and the weight of the material, but also because of the accelerating action of the rotary feeder 82.

The screw thread 74 insures rapid replacement of discharged material and continuous supply of material at this point by feeding the material in the direction of the arrow 75 into the zone 80, where it is fed downwardly by the rotary feeder 82. The latter also prevents clogging although the tendency of the screw thread to pack material, like cut string beans, against the end wall of the hopper is practically avoided by terminating the screw thread at a distance from the end wall of the hopper. As pointed out above, this distance is preferably substantially equal to the diameter of the filling opening 11.

The can receives its major charging when it is in the position occupied by can 85 in Fig. 3 under the vertical-feed zone 80. If the can is not entirely filled by the time it passes out of this zone additional material is supplied by the screw thread 74 which is feeding the material transversely over the table 10. During the entire time that the filling opening 11 is in communication with the elongated discharge outlet 67 the can has access to the material contained in the hopper. However, it has been found that the can is more quickly and completely filled by the employment of the feeding means 70 which first provides a relatively unobstructed vertical passage in the zone 80, aiding the vertical feeding at that initial point by the rotary feeder 82, and which then completes the filling by moving the material transversely over the table with the screw thread 74.

When the filling opening emerges from under the hopper the can is filled to the top with the material and the filling opening itself contains some material. To remove the excess material a rotary wiper 90 (Figs. 1, 2, and 5) is provided which comprises three flexible blades 91 mounted radially on a shaft 92 supported for rotation in a bracket 93. The wiper shaft 92 is driven from the hopper feed shaft 71 by means of bevel

gears 94 and 95. The wiper blades 91 have tongues 96 which dip into the filling openings 11 as they pass under the wiper to remove the excess material which is swept into the bowl 13 in the center of the table.

The wiper bracket 93 is supported on two vertical posts 97, 98 (Fig. 1) from a bracket 99 (Fig. 2) secured to the frame of the machine. The upper ends of the posts 97, 98 are rigidly secured in the bracket 93, while the lower ends are slideable in the bracket 99 to permit vertical adjustment of the wiper. The adjustment is retained by set screws (not shown) which are threaded through the bracket 99 and bear against the posts 97, 98. The wiper is vertically adjusted to the position shown in Fig. 5 where the tongue 96 will project down into the filling opening 11 and the remainder of the blade will sweep over the top of the table 10 as at 100 and 101.

The wiper blades 91 (Fig. 2) are constructed of a flexible material, such as linen belting, and are attached to radial fins 103 formed on a sleeve 104 which is secured to the shaft 92. The shaft 92 (Fig. 1) is supported for rotation with respect to the table 10 so that the axis of rotation will lie on a chord of the circle of movement of the filling openings. The tongues 96 (Figs. 1 and 5) are staggered on a helix around the shaft 92. The tongues are so arranged that due to the relative speed of rotation of the wiper shaft 92 and the rate of movement of the filling openings, the three tongues 96 will successively dip into each and the same filling opening 11 as it passes under the wiper. The wiper rotates in the direction of the arrow (Fig. 2) to sweep the excess material toward the center of the table 10 where it collects in the bowl 13.

Thereafter, the cans may be subjected to a packer-briner wheel 105 (Figs. 1 and 4), comprising a wheel having hollow spokes 106 terminating in presser heads 107. The hub 108 of the wheel is rotatable on a hollow axle 109 supported in a bracket 110 with its axis inclined to the axis of the table 10. A port 111 communicates with each spoke when its presser head is disposed within the filling opening 11. Brine, or syrup, is supplied to the interior of the axle 109 by a pipe 112 (Fig. 1). As the table 10 rotates, the presser heads 107 project down into the filling openings, packing the material down into the can and injecting the fluid. The packer wheel 105 is rotated by the table by engagement of the presser heads with the filling openings 11.

The operation is as follows: The empty cans are deposited on the feed disc 59 (Fig. 1) which introduces them into the pockets 19 of the feed ring 17 which carries them onto the track 20. The guide rail 25 retains the cans in the pockets 19 so that they will register with the filling openings 11 in the table 10. When each filling opening comes under the outlet 67 of the hopper 60 material descends rapidly into the can. The filling of the can is completed as the filling opening travels along under the elongated outlet 67, the screw thread 74 aiding in moving the material along the table into the can.

Excess material is removed from the can, the filling opening, and the top of the table by the wiper 90, the revolving blades of the wiper dipping into the filling openings with their tongues 96. The material is then packed down in the can by the packer wheel 105 which automatically adds the desired fluid to each can. Finally the cans are removed from the machine by the rotary discharge disc 53 and the rake 56.

While I have described a particular embodiment of the present invention, it will be obvious that various changes and modifications may be made in the details thereof without departing from the spirit of the present invention and the scope of the appended claims.

Having described my invention and in what manner the same may be used, what I claim as new and desire to protect by Letters Patent is:

1. In a machine for filling containers, such as cans or the like, with material, having means for conveying the can in registry with a traveling circular filling opening, a hopper having an elongated outlet in its bottom disposed above and extending in the direction of the path of said filling opening whereby material may gravitate from the hopper through said outlet and filling opening, said outlet being of greater length than the diameter of said filling opening whereby the filling opening travels for a distance in receiving relation to said outlet and material feeding means in said hopper to facilitate transfer of the material from said hopper through said filling opening into the can, comprising screw means to feed the material in a direction opposite to the direction of movement of the can, the discharge end of said screw means being located at a distance from the end of said elongated outlet first passed under by said filling opening, said distance being substantially equal to the diameter of said filling opening.

2. In a machine for filling containers, such as cans or the like, with material, having means for conveying the can in registry with a traveling filling opening, a hopper having an elongated outlet of greater length than the width of the filling opening, disposed above the path of said filling opening whereby the latter travels for a distance in receiving relation with said outlet, material feeding means in said hopper to facilitate transfer of the material from said hopper through said filling opening into the can, comprising a rotatable shaft in said outlet disposed parallel to the plane of said filling opening, a screw thread on said shaft extending from one end of said outlet to a point spaced apart from the other end of said outlet a distance substantially the width of said filling opening, and a pin in said shaft disposed transversely thereto with its ends projecting therefrom, said pin being located in the space between the end of said thread and the end of said outlet remote from said thread.

3. In a machine for filling containers, such as cans and the like, with material, having a rotary table provided with filling openings around its periphery in a circle, means for conveying the cans in registry with said openings, means for filling the cans with material, and means for removing excess material from the cans, comprising a rotary shaft having a plurality of blades, said shaft lying in the planes of said blades, said blades radiating from said shaft, said shaft being disposed parallel to a chord of the circle of said filling openings which chord has a length substantially equal to the length of the blades.

4. In a machine for filling containers, such as cans and the like, with material, having a rotary table provided with filling openings around its periphery in a circle, means for conveying the cans in registry with said openings, means for filling the cans with material, and means for removing excess material from the cans, comprising a rotary shaft having a plurality of blades,

said shaft lying in the planes of said blades, said blades radiating from said shaft, said shaft being disposed parallel to a chord of the circle of said filling openings, and tongues on said blades adapted to dip down into the can and remove excess material therefrom.

5. In a machine for filling containers, such as cans and the like, with material, having a rotary table provided with filling openings around its periphery in a circle, means for conveying the cans in registry with said openings, means for filling the cans with material, and means for removing excess material from the cans, comprising a rotary shaft having a plurality of blades, said shaft lying in the planes of said blades, said blades radiating from said shaft, said shaft being disposed parallel to a chord of the circle of said filling openings, and a tongue on each blade disposed in the plane of said blade and adapted to dip down into the can and remove excess material therefrom.

6. In a machine for filling containers, such as cans and the like, with material, having a rotary table provided with filling openings around its periphery in a circle, means for conveying the cans in registry with said openings, means for filling the cans with material, and means for removing excess material from the cans, comprising a rotary shaft having a plurality of blades, said shaft lying in the planes of said blades, said blades radiating from said shaft, said shaft being disposed parallel to a chord of the circle of said filling openings, and a tongue on each blade disposed in the plane of said blade and adapted to dip down into the can and remove excess material therefrom, said tongues being arranged in a helix around said shaft.

7. In a machine for filling containers, such as cans and the like, with material, having a rotary table provided with filling openings around its periphery in a circle, means for conveying the cans in registry with said openings, means for filling the cans with material, and means for removing excess material from the cans, comprising a rotary shaft having a plurality of blades, said shaft lying in the planes of said blades, said blades radiating from said shaft, said shaft being disposed parallel to a chord of the circle of said filling openings, a tongue on each blade disposed in the plane of said blade and adapted to dip down into the can and remove excess material therefrom, said tongues being arranged in a helix around said shaft, and means for rotating said shaft in timed relation with said table so that said tongues will successively enter each can as it travels under said blades.

8. In a machine for filling containers, such as cans or the like, with material, having means for conveying the can in registry with a traveling filling opening, a hopper having an elongated outlet in its bottom disposed above and extending in the direction of the path of said filling opening whereby material may gravitate from the hopper through said outlet and filling opening, said outlet being of greater length than the width of said filling opening whereby the filling opening travels for a distance in receiving relation to said outlet, and material feeding means in said hopper to facilitate transfer of the material from said hopper through said filling opening into the can, comprising the combination of screw means to feed the material toward one end of the elongated outlet, said screw means terminating a substantial distance from said end of said outlet such that it does not substantially obstruct the

filling opening when the latter first registers with said outlet at said end thereof.

9. In a machine for filling containers, such as cans or the like, with material, having means for conveying the can in registry with a traveling filling opening, a hopper having an elongated outlet in its bottom disposed above and extending in the direction of the path of said filling opening whereby material may gravitate from the hopper through said outlet and filling opening, said outlet being of greater length than the width of said filling opening whereby the filling opening travels for a distance in receiving relation to said outlet, material feeding means in said hopper to facilitate transfer of the material from said hopper through said filling opening into the can, comprising the combination of a screw positioned above said hopper outlet to feed the material toward the end of the elongated outlet first passed under by said filling opening, the threads of said screw terminating at a substantial distance from said end of said outlet, and a rotary feeder disposed over said outlet in the space between the end of said screw and said end of said outlet, to accelerate the downward discharge of material into the can.

10. In a machine for filling containers, such as cans or the like, with material, having means for conveying the can in registry with a traveling filling opening, a hopper having an elongated outlet in its bottom disposed above and extending in the direction of the path of said filling opening whereby material may gravitate from the hopper through said outlet and filling opening, said outlet being of greater length than the width of said filling opening whereby the filling opening travels for a distance in receiving relation to said outlet, and material feeding means in said hopper to facilitate transfer of the material from said hopper through said filling opening into the can, comprising the combination of a screw to feed the material toward the end of the elongated outlet first passed under by said filling opening, the discharge end of said screw being located at a distance from said end of said outlet substantially the width of the filling opening.

11. In a machine for filling containers, such as cans or the like, with material, having means for conveying the can in registry with a traveling filling opening, a hopper having an elongated outlet in its bottom disposed above and extending in the direction of the path of said filling opening whereby material may gravitate from the hopper through said outlet and filling opening, said outlet being of greater length than the width of said filling opening whereby the filling opening travels for a distance in receiving relation to said outlet, and material feeding means in said hopper to facilitate transfer of the material from said hopper through said filling opening into the can, comprising the combination of screw means positioned over said outlet to feed material into a vertical discharge zone in said hopper from which zone the material may descend through said filling opening into the can and to feed material down through the outlet portion adjacent said zone and through said filling opening as it travels below said portion of the outlet, the discharge end of said screw means being located at the margin of said zone such that it does not substantially obstruct the same.

12. In a machine for filling containers, such as cans or the like, with material, having means for conveying the can in registry with a traveling filling opening, a hopper having an elongated

outlet disposed above and extending in the direction of the path of said filling opening whereby material may gravitate from the hopper through said outlet and filling opening as the latter travels in receiving relationship with said outlet, material feeding means in said hopper to facilitate transfer of the material from said hopper through said filling opening into the can, comprising the combination of screw means positioned over said outlet to feed material into a vertical discharge zone from which zone the material may go downwardly through the portion of said hopper outlet in said

zone and through said filling opening when it registers therewith and to feed material through the hopper outlet portion adjacent said zone, and through said filling opening after the latter passes said zone, the discharge end of said screw means being located at the margin of said zone such that it does not substantially obstruct the hopper outlet portion in said zone, and a rotary feeder disposed over said outlet portion in said zone to accelerate the descent of material therefrom into the can.

EDWARD G. BAUER.
